PUMPING APPARATUS

Wade H. Wineman, Michigan City, Ind., assignor
to Joy Manufacturing Company, a corporation
of Pennsylvania

Application October 22, 1943, Serial No. 507,265

17 Claims. (Cl. 255—16)

1

My invention relates to pumping apparatus, and more particularly to apparatus for yieldingly supporting the beam of so-called "beam" well pumping equipment.

Many of the wells containing oil which ceases to flow naturally are produced by some form of "beam" well pumping equipment. The usual pumping equipment of this type includes a rigid post, and a walking beam pivotally connected between its ends to the upper end of the post. One end of the walking beam is connected through a rod line to a pump at the bottom of the well, and the other end of the beam is connected to a suitable driving unit. With such pumping equipment, where the wells are very deep, the rod line is subject to frequent breakage due to the variations in stress and the comparatively high stresses to which the rod line is subjected.

By providing a suitable yielding supporting structure for the walking beam, the maximum loads and the stress ranges on the rod line may be substantially reduced. Such supporting structure may desirably include cylinder and piston elements, one of the elements being supported in a stationary position and the other being connected to the walking beam and adapted to reciprocate relative to the first. Contained within the space between the cylinder and piston elements at one end of the cylinder is a gaseous fluid under pressure for urging the elements in extended relation so as to provide a yielding support for the walking beam. In the supporting structure illustrated herein the cylinder is mounted in a stationary upright position, and the piston is reciprocable in the cylinder and has a piston rod connected to the walking beam. This structure is similar to that shown and described in my copending application, Serial No. 357,155 now Patent No. 2,377,913 dated June 12, 1945. The structure may, however, have the piston supported in a stationary position, and have the cylinder reciprocable relative to the piston and connected to the walking beam. In order to maintain the desired pressure between the cylinder and piston elements for supporting the walking beam and its loads, improved means are provided for pumping fluid into the cylinder space to make up for fluid escaping around the piston.

It is an object of my invention to provide an improved supporting structure for a walking beam. Another object of my invention is to provide an improved pumping system. Still another object of my invention is to provide improved means for regulating the yielding resistance of a yieldable supporting structure for a walking

beam. Yet another object of my invention is to provide, in a supporting structure having a supporting element subjected to pressure fluid, improved means for regulating the pressure of the pressure fluid. Still a further object of my invention is to provide an improved means for maintaining the pressure in a fluid cushioned walking beam system. Other objects and advantages of my invention will hereinafter more fully appear.

In the accompanying drawings there is shown for purposes of illustration one form which my invention may assume in practice.

In these drawings:

Fig. 1 is a side elevational view of a pumping system in which an illustrative form of my invention is incorporated.

Fig. 2 is an enlarged vertical sectional view, partially in elevation, through the beam-supporting structure shown in Fig. 1.

Fig. 3 is a vertical sectional view similar to Fig. 2 but showing the parts in different relative positions.

In the illustrative form of the invention shown, 25 a "beam" type pumping apparatus, generally designated 1, is connected to a polished rod 2 extending through a casing head 3 of a well and connecting to a sucker rod line (not shown). The pumping apparatus includes a supporting structure, generally designated 4, a walking beam 5, and a driving unit 6 of conventional form connected by a pitman 7 with the walking beam and driven in any suitable manner.

Referring now more particularly to the supporting structure 4 for the walking beam, it will be noted that an upright cylinder 9 rests upon a lower cylinder head 10 and has a bore 11 containing a reciprocable hollow piston 12. Extending upwardly from the piston through a packing 14 in an upper cylinder head 15 is a tube-like piston rod 16 which is closed at its upper end by a wall 17. Threaded onto the upper end of the piston rod is a coupling 18 which receives the threaded end of a cylindrical shaped member 20 guided for vertical movement by a sleeve-like member 22 attached to the upper ends of supporting legs 23. Fixed to the top of the member 20, as by bolts 24, is a cap 25 to which the walking beam is pivotally connected at 26. A tank 27 containing a gaseous fluid, in this case air, under pressure is connected by a pipe 28 to a passage 29 in the lower cylinder head 10, and the passage 29 opens into a pipe 30 threaded into an opening in the lower cylinder head and extending upwardly into the piston rod.

The diameter of the pipe 30 is such as to provide between its outer surface and the inner surface of the piston rod 16, an annular space 31 through which gaseous fluid, conducted from the tank through pipe 28, passage 29 and pipe 30, may pass into the hollow piston 12. In order to seal the gaseous fluid within the tank 27 and its connected passages, and to lubricate the walls of the cylinder bore, there is placed within the lower portion of the cylinder bore a body of oil of such volume that the space within the piston is not quite filled when the piston rests upon the lower cylinder head. As the piston moves upwardly in the cylinder bore the level of the oil drops, since it then occupies space that had previously been occupied by the walls of the piston, but the length of the bore and the dimensions of the piston are such that even when the piston engages the upper cylinder head the lower end of the piston extends below the surface of the oil a substantial distance and the seal is maintained. In order to determine if there is a proper amount of oil in the cylinder, a sight glass 32 is connected in communication with the bottom of the cylinder and with a point where the pressure conditions are the same as they are at the upper surface of the oil, the point of connection herein being with the passage 29 through a passage 33 in the cylinder head 15.

Means are provided for cushioning the piston 12 as it moves toward the lower cylinder head, and this means comprises an upwardly projecting portion 34 formed on the lower cylinder head and having a sloping surface 35 which forms an annular space, between the projecting portion and the cylinder wall, having radial dimensions which gradually decrease toward the lower end of the cylinder. A flange 36 formed around the lower end of the piston is received in the annular space and partially entraps oil to cushion the piston as it moves toward the lower cylinder head.

Breathing means is provided for the upper end of the cylinder bore, and this breathing means includes a connection 37 communicating with the bore at a point spaced from the upper end of the cylinder, and communicating past a stop valve 38 with a reservoir 39 at the lower end of the latter. The upper end of the cylinder bore is connected in communication with the lower portion of the reservoir by a conduit 40 having a check valve 41, the check valve permitting a flow of fluid toward the cylinder bore and preventing fluid flow in the opposite direction. The upper portion of the reservoir is connected to atmosphere through an air cleaning venting means 43, and arranged between the upper end and lower end of the reservoir is a baffle plate 44 for effecting a separation of oil from the air discharged toward the venting means. During operation of the pumping mechanism, the valve 38 is left open so that fluid may pass freely through the connection 37 between the reservoir and the cylinder bore. As the piston 12 moves upwardly in the cylinder bore and passes the connection 37, the escape of fluid to the reservoir is cut off, and a cushioning pressure is built up in the upper portion of the cylinder bore. When the piston moves from the upper toward the lower end of the bore, the check valve 41 opens to prevent the creation of a vacuum at the upper end of the bore.

It will be noted that the pressure in the tank 27 and its connected spaces acts between the upper surface of the body of oil in the cylinder 9 and the lower surfaces of the upper end wall of the piston and the wall 17, and urges the piston in

an upward direction. To obtain the full value of alleviation this pressure should be such that, during pumping operation, the piston 12 is raised to its topmost position in the bore 11 at the same time the polished rod 2 reaches the end of its upward stroke. In order that the desired pressure may be maintained, a pump mechanism, generally designated 46, is provided for pumping oil which escapes from the lower portion of the cylinder bore between the walls of the piston and the cylinder, back into the cylinder bore beneath the piston, and for pumping air into the spaces communicating with the tank 27 so as to make up for air escaping past the piston. The pump mechanism is made adjustable, as later described, to deliver fluid to the lower end of the cylinder bore and its connected spaces at various rates. The pressure in the system may be regulated either by adjusting the pump mechanism to deliver fluid at a rate exceeding that at which fluid escapes from beneath the piston 12 and providing for the tank 27 an adjustable relief valve 47 which opens when the desired maximum pressure is exceeded, or by adjusting the pump mechanism so that fluid is delivered to the system at the same rate that it escapes from beneath the piston.

The pump mechanism 46, as shown herein, comprises a cylinder block 48 connected in any suitable manner to the piston rod 16 at a point clearing the cylinder head 15 when the piston is at the lower end of the cylinder bore. Formed in the block 48 is a bore 49 having its axis lying in a vertical plane and opening through the lower end of the block. Reciprocably mounted in the bore 49 is a piston 50 pivotally connected to a link 51 which is, in turn, pivotally connected to the walking beam 5 at one or another of the points 53 spaced varying distances from the pivot point 28. An intake port 55 opens into the upper end of the bore 49 and is connected, under control of an inlet valve 56, with a conduit 57 which communicates with a passage 58 opening through the upper surface of the piston 12. A discharge port 60 connects the upper end of the bore 49, under control of a discharge valve 61, with a conduit 62 opening into the interior of the tubular piston rod 16. The inlet and discharge valves are urged toward their closed positions, respectively, by springs 63 and 64. An adjustable abutment 65 is provided for regulating the tension of the spring 63, and a stationary abutment 66 is provided for the spring 64.

The mode of operation of the apparatus described is as follows: Air is supplied to the tank 27 from any suitable source (not shown) until the pressure built up within it and its connected spaces is sufficient to raise the piston 12 to its uppermost position in the cylinder bore 11 at the same instant the rod 2 reaches the upper end of its stroke during pumping. To maintain this pressure during pumping the relief valve 47 may be adjusted to open when the pressure exceeds this value, or the pump mechanism 46 may be adjusted by varying the closing pressure on the inlet valve and varying the stroke of the piston 50 through the connections 51 and 53, to deliver fluid to the lower end of piston 12 at the same rate that it escapes around the piston. As the walking beam is driven by the power unit 6 to reciprocate the rod 2, the piston 12 moves to various positions in bore 11 depending on the loads to which it is subjected. The pressure acting on the upper surface of the oil causes the latter to be forced gradually between the piston and the cylinder walls to the space in the bore

11 above the upper end of the piston. If the pumping apparatus is shut down for some time and a pressure is held in the tank 27, the oil will eventually all be forced to the space above the piston 12. The escape of air around the piston and from the system may be prevented by closing the valve 38. On actuation of the walking beam the piston 12 moves upwardly as the load decreases and, during normal operation, overruns the point where connection 37 opens into the cylinder bore. As the piston moves upwardly past the connection 37, fluid is compressed in the upper portion of the bore 11 and is forced through the passage 58, the conduit 57, and past the inlet valve 56 to the bore 49. As shown in Fig. 2, the walking beam is swinging in a counter-clockwise direction to raise the pump rod 2. The piston 50 is still being moved downwardly in the bore 49 by the walking beam, and the load on the beam has not yet reduced to a point where the piston 12 is raised by the pressure beneath it. When the operating conditions are ideal the piston 50 is at its lowermost position in the bore 49 when the piston 12 reaches its uppermost position in the bore 11. As the walking beam swings about the pivot 26 to lower the rod 2, the piston 50 is moved upwardly in the bore 49 and forces the fluid delivered to the bore under pressure, past the discharge valve 61 and through the conduit 62 to the interior of the piston rod 16. Fig. 3 shows the positions of the parts when the walking beam is swinging in a clockwise direction to lower the pump rod. As soon as the beam reaches the end of its swing in a clockwise direction and starts to swing in the opposite direction, the load on the beam will have increased to such an extent that the piston 12 will be forced to its lowermost position in the bore 11.

As a result of my invention there is provided an improved pumping apparatus. It will be noted that the piston for the supporting structure operates to produce a pumping action which aids in delivering fluid to the system for maintaining the desired conditions, and which acts at the same time to cushion the piston. By arranging the make up pump in the manner described there is obtained a two stage compression of fluid with the addition of a minimum amount of equipment. Other advantages will be clearly apparent to those skilled in the art.

While there is in this application specifically described one form which the invention may assume in practice, it will be understood that this form of the same is shown for purposes of illustration, and that the invention may be modified and embodied in various other forms without departing from its spirit or the scope of the appended claims.

What I claim as new and desire to secure by Letters Patent is:

1. A yieldable supporting structure adapted for association with a well pumping apparatus of the kind embodying a walking beam, comprising, in combination, means adapted to yieldingly support the walking beam and including a cylinder containing a reciprocating piston, means for supplying to the lower end of said cylinder a pressure fluid at a relatively high pressure, a vent opening into said cylinder at a point spaced from its upper end for connecting said cylinder to atmosphere, said piston moving upwardly on reduction of the load on the walking beam, covering said vent and compressing fluid within the upper portion of said cylinder, and a pump mechanism for delivering fluid from the upper to

the lower end of said cylinder, said pump mechanism including relatively reciprocable cylinder and piston elements, means including an inlet valve for connecting said cylinder element in communication with the upper portion of said cylinder, means including a discharge valve for connecting said cylinder element in communication with the lower portion of said cylinder, and means for effecting relative reciprocation of said cylinder and piston elements in such a manner that the working space in said cylinder element approaches a maximum at the time fluid is compressed in the upper portion of said cylinder.

2. A yieldable supporting structure adapted for association with a well pumping apparatus of the kind embodying a walking beam, comprising, in combination, means adapted to yieldingly support the walking beam and including a cylinder containing a reciprocating piston, means for supplying to the lower end of said cylinder a pressure fluid at a relatively high pressure; a vent opening into said cylinder at a point spaced from its upper end for connecting said cylinder to atmosphere, said piston moving upwardly on reduction of the load on the walking beam, covering said vent and compressing fluid within the upper portion of said cylinder, and a pump mechanism for delivering fluid from the upper to the lower end of said cylinder, said pump mechanism including relatively reciprocable cylinder and piston elements, inlet and discharge valve means, means including a passage opening through the upper end of said piston for connecting said cylinder element in communication with the upper portion of said cylinder past said inlet valve means, passage means for connecting said cylinder element in communication with the lower portion of said cylinder past said discharge valve means, and means for effecting relative reciprocation of said cylinder and piston elements in such a manner that the working space in said cylinder element approaches a maximum at the time fluid is compressed in the upper portion of said cylinder.

3. A yieldable supporting structure adapted for association with a well pumping apparatus of the kind embodying a walking beam, comprising, in combination, means adapted to yieldingly support the walking beam and including a cylinder containing a reciprocating piston, means for supplying to the lower end of said cylinder a pressure fluid at a relatively high pressure, a vent opening into said cylinder at a point spaced from its upper end for connecting said cylinder to atmosphere, said piston moving upwardly on reduction of the load on the walking beam, covering said vent and compressing fluid within the upper portion of said cylinder, and a pump mechanism for delivering fluid from the upper to the lower end of said cylinder, said pump mechanism including relatively reciprocable cylinder and piston elements, means connecting said cylinder element for movement with said piston, means connecting said piston element for actuation by the walking beam, said piston element being so actuated that the working space in said cylinder element approaches a maximum when fluid is compressed in the upper portion of said cylinder, and means including inlet and discharge valves for connecting said cylinder element in communication, respectively, with the upper and lower ends of said cylinder.

4. A yieldable supporting structure adapted for association with a well pumping apparatus of the kind embodying a walking beam, comprising, in

combination, means adapted to yieldingly support the walking beam and including a cylinder containing a reciprocatory piston, means for supplying to the lower end of said cylinder a pressure fluid at a relatively high pressure, a vent opening into said cylinder at a point spaced from its upper end for connecting said cylinder to atmosphere, said piston moving upwardly on reduction of the load on the walking beam, covering said vent and compressing fluid within the upper portion of said cylinder, and a pump mechanism for delivering fluid from the upper to the lower end of said cylinder, said pump mechanism including relatively reciprocable cylinder and piston elements, means connecting one of said cylinder and piston elements for movement with said piston, means connecting the other of said elements for actuation by said walking beam, said connecting means operating to effect relative reciprocation of said cylinder and piston elements in such a manner that the working space in said cylinder element approaches a maximum when fluid is compressed in the upper portion of said cylinder, and means including inlet and discharge valves for connecting said cylinder element in communication, respectively, with the upper and lower ends of said cylinder.

5. A yieldable supporting structure adapted for association with a well pumping apparatus of the kind embodying a walking beam, comprising, in combination, means adapted to yieldingly support the walking beam and including a cylinder containing a reciprocatory piston, means for supplying to the lower end of said cylinder a pressure fluid at a relatively high pressure, a vent opening into said cylinder at a point spaced from its upper end for connecting said cylinder to atmosphere, said piston moving upwardly on reduction of the load on the walking beam, covering said vent and compressing fluid within the upper portion of said cylinder, and a pump mechanism for delivering fluid from the upper to the lower end of said cylinder, said pump mechanism including relatively reciprocable cylinder and piston elements, means connecting said cylinder element for movement with said piston, means for adjustably connecting said piston element to the walking beam at points spaced from the point of support of the latter, said piston element being so actuated that the working space in said cylinder element approaches a maximum when fluid is compressed in the upper portion of said cylinder, and means including inlet and discharge valve means for connecting said cylinder element in communication, respectively, with the upper and lower ends of said cylinder.

6. A yieldable supporting structure adapted for association with a well pumping apparatus of the kind embodying a walking beam, comprising, in combination, means adapted to yieldingly support the walking beam and including a cylinder containing a reciprocatory piston, an enclosed tank containing air at a relatively high pressure, means for connecting said tank in communication with the lower end of said cylinder, a vent opening into said cylinder at a point spaced from its upper end, said piston moving upwardly on reduction of the load on the walking beam, covering said vent and compressing air within the upper portion of said cylinder, pump mechanism for delivering air under pressure from the upper to the lower end of said cylinder, said pump mechanism including relatively reciprocable cylinder and piston elements, means including inlet and discharge valves connecting said cylinder element in communication, respectively, with the cylinder spaces at the upper and lower ends of said piston, and means for effecting relative reciprocation of said cylinder and piston elements in such a manner that the working space in said cylinder element approaches a maximum at the time fluid is compressed in the upper portion of said cylinder.

element in communication, respectively, with the cylinder spaces at the upper and lower ends of said piston, means for effecting relative reciprocation of said cylinder and piston elements in such a manner that the working space in said cylinder element approaches a maximum at the time fluid is compressed in the upper portion of said cylinder, and means including a relief valve for regulating the pressure in the space beneath said piston.

7. A yieldable supporting structure adapted for association with a well pumping apparatus of the kind embodying a walking beam, comprising, in combination, means adapted to yieldingly support the walking beam and including a cylinder containing a reciprocatory piston, an enclosed tank containing air at a relatively high pressure, means for connecting said tank in communication with the lower end of said cylinder, a vent opening into said cylinder at a point spaced from its upper end, said piston moving upwardly on reduction of the load on the walking beam, covering said vent and compressing air within the upper portion of said cylinder, pump mechanism for delivering air under pressure from the upper to the lower end of said cylinder, said pump mechanism including a cylinder element connected for reciprocation with said piston, a piston element received within said cylinder element and connected for actuation by the walking beam, said piston element being so actuated that the working space in said cylinder element approaches a maximum when fluid is compressed in the upper portion of said cylinder, means including inlet and discharge valves connecting said cylinder element in communication, respectively, with the cylinder spaces at the upper and lower ends of said piston, and means including a relief valve for regulating the pressure in the space beneath said piston.

8. A yieldable supporting structure adapted for association with a well pumping apparatus of the kind embodying a walking beam, comprising, in combination, means adapted to yieldingly support the walking beam and including a cylinder containing a reciprocatory hollow piston open at its lower end, a liquid within the lower portion of said cylinder for sealing the lower end of said piston against the escape of fluid from within the latter during normal operation of said pumping apparatus, a vent opening into said cylinder at a point spaced from its upper end, means for supplying gaseous fluid at a relatively high pressure to the space within said hollow piston, said piston moving upwardly on reduction of the load on the walking beam, covering said vent and compressing fluid within the upper portion of said cylinder, and a pump mechanism for delivering fluid from the upper to the lower end of said cylinder during operation of said pumping apparatus, said pump mechanism including relatively reciprocable cylinder and piston elements, means including inlet and discharge valves for connecting said cylinder element in communication, respectively, with the cylinder spaces at the upper and lower ends of said piston, and means for effecting relative reciprocation of said cylinder and piston elements in such a manner that the working space in said cylinder element approaches a maximum at the time fluid is compressed in the upper portion of said cylinder.

9. A yieldable supporting structure adapted for association with a well pumping apparatus of the kind embodying a walking beam, comprising, in combination, means adapted to yieldingly sup-

port the walking beam and including a cylinder containing a reciprocatory hollow piston open at its lower end, a liquid within the lower portion of said cylinder for sealing the lower end of said piston against the escape of fluid from within the latter during normal operation of said pumping apparatus, a vent opening into said cylinder at a point spaced from its upper end, means for supplying gaseous fluid at a relatively high pressure to the space within said hollow piston, said piston moving upwardly on reduction of the load on the walking beam, covering said vent and compressing fluid within the upper portion of said cylinder, and a pump mechanism for delivering fluid from the upper to the lower end of said cylinder during operation of said pumping apparatus, said pump mechanism including relatively reciprocable cylinder and piston elements, one of said elements connected for reciprocation with said piston and the other element connected for actuation by the walking beam, said connecting means operating to effect relative reciprocation of said cylinder and piston elements in such a manner that the working space in said cylinder element approaches a maximum when fluid is compressed in the upper portion of said cylinder, means including an inlet valve for connecting said cylinder element in communication with the cylinder space at the upper end of said piston, and means including a discharge valve for connecting said cylinder element in communication with the cylinder space at the lower side of said piston.

10. A yieldable supporting structure adapted for association with a well pumping apparatus of the kind embodying a walking beam, comprising, in combination, means adapted to yieldingly support the walking beam and including a cylinder containing a reciprocatory hollow piston open at its lower end, a liquid within the lower portion of said cylinder for sealing the lower end of said piston against the escape of fluid from within the latter during normal operation of said pumping apparatus, a vent opening into said cylinder at a point spaced from its upper end, means for supplying gaseous fluid at a relatively high pressure to the space within said hollow piston, said piston moving upwardly on reduction of the load on the walking beam, covering said vent and compressing fluid within the upper portion of said cylinder, and a pump mechanism for delivering fluid from the upper to the lower end of said cylinder during operation of said pumping apparatus, said pump mechanism including relatively reciprocable cylinder and piston elements, means connecting said cylinder element for reciprocation with said piston, means connecting said piston element for actuation by the walking beam, said piston element being so actuated that the working space in said cylinder element approaches a maximum when fluid is compressed in the upper portion of said cylinder, and means including inlet and discharge valves for connecting said cylinder element in communication, respectively, with said cylinder at the upper and lower ends of said piston.

11. In an apparatus of the character described, in combination, a walking beam, means for yieldingly supporting the walking beam including relatively reciprocable cylinder and piston elements, one pivotally connected to the walking beam and the other constituting a stationary support, the weight of the walking beam tending to diminish the space at one side of the piston and to increase the space at the other side, means

for maintaining a volume of compressible fluid under pressure in communication with the space at the first mentioned side of said piston, and means for delivering fluid from the second mentioned side of the piston to the first mentioned side thereof including a pump having relatively movable parts cooperating to form a working chamber and further having an intake connected with the second mentioned side of the piston and a discharge connected with the first mentioned side of the piston, and means for effecting relative movement between said relatively movable parts providing maximum volume of said working chamber when the volume at the second mentioned side of the piston is at a minimum.

12. In an apparatus of the character described, in combination, a walking beam, means for yieldingly supporting the walking beam including relatively reciprocable cylinder and piston elements, one pivotally connected to the walking beam and the other constituting a stationary support, the weight of the walking beam tending to diminish the space at one side of the piston and to increase the space at the other side, means for maintaining a volume of compressible fluid under pressure in communication with the space at the first mentioned side of said piston, and means for delivering fluid from the second mentioned side of the piston to the first mentioned side thereof including a pump operated by said walking beam and having relatively movable parts cooperating to form a working chamber and further having an intake connected with the second mentioned side of the piston and a discharge connected with the first mentioned side of the piston, and means connected to said walking beam for effecting relative movement between said relatively movable parts providing maximum volume of said working chamber when the volume at the second mentioned side of the piston is at a minimum.

13. In an apparatus of the character described, in combination, a walking beam, means for yieldingly supporting the walking beam including relatively reciprocable cylinder and piston elements, one pivotally connected to the walking beam and the other constituting a stationary support, the weight of the walking beam tending to diminish the space at one side of the piston element and to increase the space at the other side, means for maintaining a volume of compressible fluid under pressure in communication with the space at the first mentioned side of said piston element, the one of said elements connected to the walking beam operating on the reduction of the load thereon to reduce the space at the second mentioned side of said piston element, and means for delivering fluid from the second mentioned side of said piston to said first mentioned side including a pump having a cylinder supported by the one of said elements pivotally connected to the walking beam, and a piston connected to the walking beam for actuation thereby, said piston so actuated that the working space in said pump cylinder approaches a maximum when the space at the second mentioned side of said piston element approaches a minimum.

14. In an apparatus of the character described, in combination, a walking beam, means for yieldingly supporting the walking beam including relatively reciprocable cylinder and piston elements, one pivotally connected to the walking beam and the other constituting a stationary support, the weight of the walking beam tending to diminish the space at one side of the piston and to increase the space at the other side, means for main-

taining a volume of compressible fluid under pressure in communication with the space at the first mentioned side of said piston, the one of said elements connected to the walking beam operating on the reduction of the load thereon to reduce the space at the second mentioned side of said piston, and means for delivering fluid from the second mentioned side of said piston to said first mentioned side including a pump having relatively movable pumping elements, one of said pumping elements supported by the one of said piston and cylinder elements connected to the walking beam, and the other of said pumping elements connected to the walking beam for actuation thereby, said pumping element connected to the walking beam being so actuated thereby that the working space in said pump approaches a maximum when the space at the second mentioned side of said piston approaches a minimum.

15. In an apparatus of the character described, in combination, a walking beam connected at one end to a load to be reciprocated, means for yieldingly supporting the walking beam at a point between its ends including relatively reciprocable cylinder and piston elements, one pivotally connected to the walking beam and the other constituting a stationary support, the weight of the walking beam and its load tending to diminish the space at one side of the piston and to increase the space at the other side, means for connecting a volume of compressible fluid under pressure in communication with the space at the first mentioned side of said piston, and means for delivering fluid from the second mentioned side of said piston to said first mentioned side including a pump having relatively movable pumping elements, one of said pumping elements supported by the one of said piston and cylinder elements connected to the walking beam, and the other of said pumping elements connected to the walking beam at a point spaced from its pivotal support and at the side of the latter opposite the load to be reciprocated, said last mentioned pumping element being so actuated as to effect an increase in the working space in said pump as the load on the walking beam is decreased.

16. In an apparatus of the character described, in combination, a walking beam connected at one end to a load to be reciprocated, means for yieldingly supporting the walking beam at a point between its ends including relatively reciprocable cylinder and piston elements, one pivotally connected to the walking beam and the other constituting a stationary support, the weight of the

walking beam and its load tending to diminish the space at one side of the piston element and to increase the space at the other side, means for connecting a volume of compressible fluid under pressure in communication with the space at the first mentioned side of said piston element, the one of said elements connected to the walking beam operating on the reduction of the load thereon to reduce the space at the second mentioned side of said piston element, and means for delivering fluid from the second mentioned side of said piston element to said first mentioned side including a pump having relatively reciprocable cylinder and piston members, one of said members supported by the one of said cylinder and piston elements connected to the walking beam, and the other of said members connected to the walking beam at a point spaced from its pivotal support, said cylinder and piston members so arranged that the working space in said cylinder member is increased as the walking beam operates to lift the load.

17. In an apparatus of the character described, in combination, a walking beam, means for yieldingly supporting the walking beam including relatively reciprocable cylinder and piston elements, one pivotally connected to the walking beam and the other constituting a stationary support, the weight of the walking beam tending to diminish the space at one side of the piston and to increase the space at the other side, means for venting said cylinder element to atmosphere at a point to be uncovered by said piston element as the space at the second mentioned side of said piston is increased, the one of said elements connected to the walking beam operating on the decrease of load thereon to cut off said venting means and effect an increase in pressure at the second mentioned side of said piston, means for maintaining a volume of compressible fluid under pressure in communication with the space at the first mentioned side of said piston, and means for delivering fluid from the second mentioned side of the piston to the first mentioned side thereof including a pump having relatively movable parts cooperating to form a working chamber and further having an intake connected with the second mentioned side of the piston and a discharge connected with the first mentioned side of the piston, and means for effecting relative movement between said relatively movable parts providing maximum volume of said working chamber when the volume at the second mentioned side of the piston is at a minimum.

WADE H. WINEMAN.
